UNITED STATES PATENT OFFICE.

GEORGE FARGHER HIGHT AND THOMAS WILLIAM BROWN, OF AUCKLAND, NEW ZEALAND.

STOP FOR SLIDING WINDOW SASHES AND THE LIKE.

Application filed February 24, 1923. Serial No. 621,053.

To all whom it may concern:

Be it known that we, GEORGE FARGHER HIGHT and THOMAS WILLIAM BROWN, both citizens of the Dominion of New Zealand, and both residing at Woodbank Studio, Three Kings Road, Mt. Eden, Auckland, in the Provincial District of Auckland, New Zealand, have invented an Improved Stop for Sliding Window Sashes and the like, of which the following is a specification.

This invention relates to sliding sashes and the like which are operated in guides, without the aid of balance weights, and has for its object the provision of improved means, designed to hold sashes or the like in any position in the guides without the necessity of adjusting screws or catches and which also enables said sashes or the like to be moved without having to release or withdraw screws, catches or other holding means.

According to the invention the outer edges of a sash or sliding frame, contain recesses in which are located springs in compression said springs exerting outward pressure on plates which slide with the sash and are forced by the springs against the guides in which the sash or frame works.

One or more springs and sliding plates are provided at opposite edges of the sash or frame.

In the drawing accompanying this specification—

Figure 1 is a sectional elevation of portion of a sash and a guide in which the latter works, fitted with the improved stop.

Figure 2 is an elevation of a plate attached to the sash.

Figure 3 an elevation of the spring pressed sliding plate and

Figure 4 an elevation of a sash fitted with the invention at opposite edges.

The opposite members 1 of a sash or frame are recessed in their outer edges to take a plate 2 containing a socket 3, and also a sliding plate 4 the latter being provided with studs 5 which enter holes 5^a in the plate 2.

The plate 2 is attached by screws 2^a to the member 1.

The plate 4 is also recessed into the members 1.

The socket 3 contains a cylindrical casing 6 closed at one end and in which is placed a spiral spring 7 in compression, the latter acting between the inner end of the socket 3 and the closed end of the casing 6 to force said closed end against the plate 4 and so keep the latter pressed outwards against the guide 8. A metal wearing strip 9 is attached to the guide 8 by screws 9^a the plate 4 sliding against said strip 9.

The means shown in Figure 1 are fitted one or more to each side of the sash or frame as shown in Figure 4.

The expansion of the springs 7, forces the plates 4 outwards against the guides 8 and are of sufficient strength to retain the sash or frame stationary between the guides 8 in whatever position it is left. At the same time said springs do not prevent the sash or frame from being raised or lowered in the guides.

The means above described besides acting to hold the sash or frame stationary between the guides 8, also prevent said sash or frame from rattling in its guides.

What we do claim and desire to obtain by Letters Patent of the United States of America is:—

An improvement of the character described, comprising, a sash, a guide frame for the sash, a pressing means, including an apertured socketed plate recessed into and fixed to an edge of the sash, a slide plate recessed into the said edge of the sash and having pins received in the apertures of the socketed plate, a thimble casing positioned in the socket of the plate with its closed end against the sliding plate, and an expanding spring bearing against the end of the socket and the end of the thimble casing, and forcing the sliding plate against the guide frame.

In testimony whereof we have signed our names to this specification in the presence of two witnesses.

GEORGE FARGHER HIGHT.
THOMAS WILLIAM BROWN.

Witnesses:

WILLIAM PINCHES,
MARY PICKINGTON.
